UNITED STATES PATENT OFFICE.

JOHN FRANCIS O'MALLEY, OF MERIDEN, CONNECTICUT.

MACHINE-GUN.

1,307,316.

Specification of Letters Patent. Patented June 17, 1919.

Application filed July 17, 1917. Serial No. 181,024.

To all whom it may concern:

Be it known that I, JOHN F. O'MALLEY, a subject of the King of Great Britain, and a resident of Meriden, in the county of New Haven and State of Connecticut, have invented a new and Improved Machine-Gun, of which the following is a full, clear, and exact description.

My invention has for an object to provide a machine gun which is extremely simple and light in construction and which may be fired rapidly under all conditions. The machine gun is provided with a double reversible barrel which may be adjusted to permit one barrel to cool while the other barrel is in use, and the rapidity of fire may be regulated by the adjustment of the gears which connect the operating member with the loading and firing mechanism. The hammer is operated by the cartridge wheel, and the cartridge wheel and the hammer are covered by a cap which may be readily removed to correct any trouble which may arise when firing the gun and also to clean the mechanism.

Additional objects of the invention will appear in the following specification in which the preferred form of the invention is disclosed.

In the drawings similar reference characters denote similar parts in all the views, in which—

Figure 1 is a side elevation of the machine gun, parts being broken away to illustrate the construction;

Fig. 2 is a sectional view on the line 2—2 of Fig. 3;

Fig. 3 is a sectional view on the line 3—3 of Fig. 2;

Fig. 4 is a sectional view on the line 4—4 of Fig. 2;

Fig. 5 is a sectional view on the line 5—5 of Fig. 2;

Fig. 6 is a sectional view on the line 6—6 of Fig. 2; and

Fig. 7 is a front elevation of the barrel member.

By referring to the drawings it will be seen that the machine gun body is provided with a base 10 having an upwardly extending lug 11 which is spaced from the sides, and from the front and from the rear of the base 10; disposed on the base 10 at the sides of the lug 11 there are side plates 12 and disposed between the side plates 12 and at the rear of the lug 11 there is a block 13,

another block 14 being disposed at the front of the lug 11 and between the side plates 12. The side plates 12 are secured to the lug 11 by means of a bolt 15, the block 13 is secured in position between the side plates by means of bolts 16, and the block 14 is secured between the side plates by means of bolts 17. There are bearings 18 and 19 on the block 13 between which there is an opening 20, and there is a bearing 21 in the block 14. Journaled in these bearings 18, 19, and 21 there is a shaft 22, a cartridge wheel 23 being disposed between the blocks 13 and 14 and being secured to the shaft 22 for rotating with the latter. The cartridge wheel 23 has radial projections 24 and 25 which are spaced apart so that when the cartridge tape 26 is disposed around the cartridge wheel 23 between the projections 24 and 25 the forward and rear ends of the cartridges will fit the spaces between the radial projections 24 and 25 in a manner readily understood.

Disposed at the rear of the cartridge wheel and secured for rotating therewith there is a cam member 27 which is disposed for engagement with the forward end of a hammer 28 which is disposed in an opening 29 in the block 13. The hammer 28 has a rearwardly extending stud 30 which fits into a bearing 31 at the rear of the opening 29 and around this stud 30 there is disposed a spring 32 for holding the hammer 28 yielding forward. Disposed at the rear of the cartridge wheel and adjacent the cam member 27 there is a block 33 which has in its upper surface a groove 34 for receiving the firing pin 35 which extends forwardly from the hammer 28. This firing pin 35 being disposed in position to engage a cartridge which has been moved by the cartridge wheel 23 to the firing position, the cam member 27 being so adjusted relatively to the hammer 28, that the hammer 28 and with it the firing pin 35 will be moved rearwardly immediately preceding the movement of the cartridge to firing position the cam permitting the hammer 28 to move forward and with it the firing pin 35 immediately on the cartridge moving to the position in which it should be fired. Disposed over the cartridge wheel 23, the block 33 and the forward portion of the hammer 28 there is a cap 36 which with the cartridge wheel 23 forms a chamber for the cartridge which is to be fired. This cap 36 is normally held in

place by a screw bolt 37, which however, may be quickly removed to correct any fault should the firing mechanism become jammed. Extending forwardly from the block 14 there is a stud 37* on which a barrel member 38 is rotatably mounted. The inner end of the barrel member 38 has a web portion 39 disposed between the two barrels 40, and which fits in an opening 41 at the front of the block 14, it being possible to move the barrel member 38 forwardly and rotate it 180 degrees to change the barrel and to dispose the cooled barrel in alignment with the barrel opening 42 in the block 14 which extends from the firing position of the cartridge. In this way the barrel which has been fired for a period may be cooled while the second barrel is in use. When the barrel member 38 is disposed in position it is held in place by means of a stud screw 43.

In addition to the bearings 18 and 19 there is another bearing 44 in the block 13 in which a shaft 45 is journaled, gearing 46 connecting the shafts 45 and 22 so that the shaft 22 may be rotated by a crank 46* on the shaft 45. It will be understood that the gears connecting the shafts 45 and 22 may be changed as may be desired to regulate the rapidity of firing, although the crank 46* may in all cases be rotated at the same speed.

The opening 29 in the block 13 extends for a distance through the side of said block to permit the introduction of the hammer.

28. In the cap 36 there are transverse openings 47 which are provided to assist in keeping the cap 36 cool. The barrel member 38 has two front sights 48, one for each of the barrels, the front sight 48 which extends upwardly from the barrel which is in use coöperating with a rear sight 49, which is mounted at the rear of the block 13.

There are openings 50 in the side plates 12 through which the cartridge tape 26 may pass.

45. The base 10 has a depending member 51 with worm teeth 52 with which meshes a worm wheel 53 journaled in bearings in a bracket 54 to which the depending member 51 is pivoted on a transverse axis as 55. The worm wheel 53 may be rotated by the hand wheel 56 to elevate or depress the gun barrel. The bracket 54 is pivoted on a vertical axis to a tripod or other support 57.

Having thus described my invention I claim as new and desire to secure by Letters Patent:

1. In a machine gun, a gun body having an opening extending through its outer surface, a cartridge wheel rotatably mounted in the opening, a hammer having means for firing a cartridge which has been moved to a firing position by the cartridge wheel, and a cap for covering the opening which forms with the cartridge wheel a chamber for the cartridge.

2. In a machine gun, a gun body having an opening extending through its outer surface, means in the opening for moving a cartridge into firing position, a hammer having means for firing the cartridge after it has been moved to firing position by the said means, and a cap for covering the opening which forms with the said means a chamber for the cartridge. 70

3. In a machine gun, a gun body having an opening extending through its outer surface, means to move a cartridge to firing position in the opening, a block disposed in the rear of the said firing position and provided with a groove in its outer surface, a firing pin in the groove, a cap disposed against the block at the firing pin for holding the latter in position, and means to operate the firing pin. 75

4. In a machine gun, a gun body having an opening extending through its outer surface, a cartridge wheel rotatably mounted in the opening, a hammer having means for firing a cartridge which has been moved to firing position by the cartridge wheel, a 90 spring for holding the hammer yieldingly in one direction, a cam rotatable by the cartridge wheel for moving the hammer in an opposite direction, and a cap for covering the opening which forms with the cartridge wheel a chamber for the cartridge, the cap being removable to correct trouble at the cartridge wheel. 95

5. In a machine gun, a gun body having an opening extending through its outer surface, a cartridge wheel rotatably mounted in the opening, a block disposed at the rear of the cartridge wheel, a firing pin disposed on the block for firing a cartridge which has been moved into operative position by the cartridge wheel, means on the cartridge wheel for operating the firing pin, and a cap for covering the opening in the gun body and which forms with the cartridge wheel a chamber for the cartridge. 100

6. In a machine gun, a cartridge wheel, a hammer for firing the cartridge moved to operative position by the carriage wheel, means on the cartridge wheel for operating the hammer, and a removable cap which forms with the cartridge wheel a chamber for the cartridge. 115

7. In a machine gun, a gun body having an opening extending through its outer surface, means to move a cartridge to firing position in the opening, a block disposed in the rear of the said firing position and provided with a groove in its outer surface, a firing pin in the groove, a cap for closing the opening in the body and disposed against the block for holding the firing pin in position thereon, and means to operate the firing pin. 120

8. In a machine gun, a gun body having an opening extending through its rear and through the body intermediate its forward 130

and rear ends, a block for closing the opening at the rear of the body and provided with a bearing, a shaft journaled in the bearing, a cartridge wheel mounted on the shaft to rotate with the latter, a cap for closing the opening intermediate the forward and rear ends of the body, means to rotate the shaft and means for firing a cartridge which has been moved into firing position by the cartridge wheel.

9. In a machine gun, a gun body having an opening extending through its outer surface, bearings in the body in the front and at the rear of the opening, a shaft journaled in the bearings, a cartridge wheel mounted on the shaft for rotating with the latter, a cap for covering the opening which may be removed to correct trouble at the cartridge wheel, the cap forming with the cartridge wheel a chamber for the cartridge, means for firing a cartridge moved to firing position by the cartridge wheel, and means to rotate the shaft.

10. In a machine gun, a gun body having an opening extending through its top and rear, means in the opening for moving a cartridge into firing position, a block fitted between the sides of the body at the rear of the opening, a cap for closing the top of the opening, and means for firing a cartridge which has been moved into firing position by the first mentioned means.

11. In a machine gun, a gun body having an opening extending through its top and rear, means in the opening for moving a cartridge into firing position, a block fitted between the sides of the body at the rear of the opening, a cap for closing the top of the opening, means for firing a cartridge which has been moved into firing position by the first mentioned means, means carried by the block for operating the second mentioned means, and means on the first means for operating the third means.

12. In a machine gun, a gun body having an opening extending through its top and rear, means in the opening for moving a cartridge into firing position, a block having an opening fitting in the rear of the gun body opening for closing the rear of the latter, a cap for closing the top of the gun body opening; a hammer in the opening in the block, resilient means in the block opening for holding the hammer yieldingly in position, means by which the hammer is adapted to fire a cartridge which has been moved into firing position by the first means, and means operated by the first means and disposed in front of the hammer for actuating the latter.

13. In a machine gun, a gun body having an opening extending through its top and rear, a bearing in the gun body at the front of the opening, a block fitted in the rear of the gun barrel opening for closing the rear

of the latter, a bearing in the block, a shaft journaled in the bearings, a cartridge wheel disposed in the opening and mounted on the shaft to be rotated by the latter, a cap for closing the top of the gun body opening, and means for firing a cartridge which has been moved into firing position by the cartridge wheel, operable by the shaft.

14. In a machine gun, a gun body having an opening extending through its top and rear, a bearing in the gun body at the front of the opening, a block fitted in the rear of the gun barrel opening for closing the rear of the latter, a bearing in the block, a shaft journaled in the bearings, a cartridge wheel disposed in the opening and mounted on the shaft to be rotated by the latter, a cap for closing the top of the gun body opening, means for firing a cartridge which has been moved into firing position by the cartridge wheel, operable by the shaft, a second bearing in the block, a second shaft journaled in the second bearing, gearing connecting the shaft and means to rotate the second mentioned shaft.

15. In a machine gun, a gun body having a central portion with openings extending through its top and through its sides, the bottom and the sides of the gun body extending rearwardly beyond the central portion, means in the opening for moving a cartridge into firing position, a removable block provided with an opening disposed on the rearwardly extending portion of the gun body and fitted between the gun body sides at the rear of the opening, a cap disposed in the upper portion of the opening in the gun body for closing the opening at the top of the gun body, a hammer in the opening in the block having means for firing the cartridge which has been moved into firing position by the first mentioned means, and means operable by the first mentioned means for actuating the hammer.

16. In a machine gun, a gun body having a bottom and sides, there being an opening in the gun body which extends through the top, the front and the rear of the gun body, a barrel block disposed on the forward portion of the bottom of the gun body and secured between the sides of the gun body, a block disposed on the rear of the bottom of the gun body and secured between the sides of the gun body, a cap disposed between the top of the blocks for closing the top of the opening between the blocks, means in the opening between the blocks for moving a cartridge into firing position, and means for firing the cartridge when moved to said position.

17. In a machine gun, a gun body having an opening extending through its top and rear, means in the opening for moving a cartridge into firing position, a removable block having an opening fitted between the

- sides of the body at the rear of the opening, a cap for closing the top of the opening in the gun body, which forms with the said means a chamber for the cartridge, a hammer in the opening in the block having means for firing the cartridge which has been moved into firing position by the first mentioned means, and means operable by the first mentioned means for actuating the hammer.
- 10 18. A machine gun body having an opening which extends through the top, front and rear of the body, a block fitted between the sides of the body at the rear of the opening, another block fitted between the sides of the body at the front of the opening, a cap for covering the opening between the blocks, and a loading and firing means in the opening between the blocks.
- 15 19. A machine gun body having an opening which extends through the top, front and rear of the body, a block fitted between the sides of the body at the rear of the opening, another block fitted between the sides 25 of the body at the front of the opening, a cap for covering the opening between the blocks, a loading and firing means in the opening between the blocks, a forwardly extending spindle on the second block, and a 30 barrel member rotatably mounted on the spindle and having a plurality of barrels any one of which may be moved into operative position by the rotation of the barrel member relatively to the machine gun body.
- 35 20. In a machine gun, a base member having an upwardly extending lug spaced from its sides and its ends, two side plates resting on the base at the sides of the lug and secured thereto, two blocks disposed between the plates, one at the rear and one at the

front of the lug, a cap for covering the space between the blocks, and a loading and firing means disposed between the blocks.

21. In a machine gun, a gun body having an opening oblong in cross section, a stud 45 extending in the opening and beyond the gun body, a barrel member mounted on the stud and having its breach normally fitting the opening to prevent rotation, it being possible to move the barrel member forward, rotate it, and move it back again to normal position, and means for holding the barrel member in normal position.

22. In a machine gun, a gun body having an opening extending through its outer surface, means to move a cartridge to firing position in the opening, a block disposed in the rear of the said firing position and provided with a groove in its outer surface, a firing pin in the groove, a cap disposed 55 against the block for holding the firing pin in position and forming with the means a chamber for a cartridge, and means to operate the firing pin.

23. In a machine gun, a gun body having an opening extending through its rear and through the body intermediate its forward and rear ends, a block for closing the opening at the rear of the body and provided with a bearing, a shaft journaled in the 65 bearing, a cartridge wheel mounted on the shaft to rotate with the latter, a cap for closing the opening intermediate the forward and rear ends of the body and forming with the cartridge wheel a cartridge 70 chamber, means to rotate the shaft, and means for firing a cartridge which has been moved into firing position by the cartridge wheel.

JOHN FRANCIS O'MALLEY.
